UNITED STATES PATENT OFFICE.

RUSSELL WILES, OF RIVERSIDE, ILLINOIS.

CAMPER'S BED.

1,401,846.

Specification of Letters Patent. Patented Dec. 27, 1921.

Application filed May 7, 1915. Serial No. 26,447.

To all whom it may concern:

Be it known that I, RUSSELL WILES, a citizen of the United States, residing at Riverside, in the county of Cook and State of Illinois, have invented a new and useful Improvement in Campers' Beds, of which the following is a specification.

My invention relates to certain new and useful improvements in a camper's bed, and 10 is fully described and explained in the specification and shown in the accompanying drawings, in which:

Figure 1 is a side elevation of the improved bed; Fig. 2 is a top plan; Fig. 3 is a 15 section on the line 3 of Fig. 1; Fig. 4 is a top plan showing the cross ribs; Fig. 5 is a section on the line 5 of Fig. 4; Figs. 6 and 7 are detailed sections on opposite sides of the bed on the same plane as Fig. 3, and Fig. 8 20 is a detailed section on the line 8 of Fig. 2.

Referring to the drawings, it will be seen that the bed consists of two principal parts, a hammock, and a tent shelter thereover and secured thereto. The hammock has a central 25 web 9 of strong cloth, hemmed at the ends to receive spreaders 10, preferably of bamboo, and is provided with supporting cords 11 at its two ends, the cords radiating from rings 12 at the ends of the hammock, to which are 30 also secured suspending ropes 13. The triangular end spaces formed by the cords 11 are covered with mosquito netting or bobbinet 14 so as to permit ventilation from below even when the state of the weather compels 35 the closing of the tent ventilators or windows.

The tent part is of the wedge or A type with rope ridge but somewhat modified from the common form. The tent ridge rope is 40 shown at 15, the tent sides being indicated by 16. On the top of the tent are cross ribs 17 of flexible wire. These operate to take up any slack in the sides so as to give increased head room and provide a very desirable general elasticity preventing too great strain on 45 the tent sides. The ridge stops above the hammock spreaders and the ends are brought down in pointed form to the outer cords of the hammock.

50 The tent sides hang below the outer edges of the hammock to shed water entirely clear thereof, and to prevent the bottom of the hammock from getting wet. The tent is secured to the hammock by providing on the inner side of the tent walls a strip of fabric, 55 18, sewed on its median line to the tent so as

to afford two long flaps between which the hammock edge is received, a lacing cord being passed through to make all fast. This strip 18 goes entirely around the inside of 60 the tent (except on a part of one side), and is laced over the outer cords at the ends, the netting 14 being doubled over the cords 11 before lacing the tent part so that the netting is simply and firmly secured, and yet can be 65 easily renewed when desired.

For a space of perhaps five feet along one edge of the hammock the strip 18 is omitted, and a wide strip 19 (Fig. 7) is secured to the tent in its place. The hammock and tent are 70 provided with tapes 20 to be tied together under the strip 19, which is then laid flat in the hammock, and extends far enough in to make a fly-proof edge. In practice this strip 19 is about nine inches wide and tucks under 75 the bedding so as to make tightness on this edge certain. The user, of course, enters the structure through the opening afforded between hammock and tent when these tapes 20 are untied, tying the tent shut after he is 80 inside. Windows 21 are preferably provided in the tent for ventilation and to permit looking out without opening the tent. They are of ordinary form, filled with netting and 85 closed when desired by flaps which can be manipulated from within.

The bed is provided with its under bedding beneath the weight-supporting web 9. The arrangement is shown in the sectional views (Figs. 3, 6, 7 and 8), from which it 90 will be seen that the main hammock web 9 has below it a looser piece, 21^a, and between the two is an insulating medium 22. This may be wool or down, and it may be removable or not as is preferred. If made removable the web 21^a is loose along one edge and laces with the hammock edge between the edges of the strip 16 (Fig. 6). But the insulation may simply be loosely quilted in place between the webs 9 and 21^a. One point, 100 however, is important. The web 9 carries the weight of the occupant, no substantial part thereof being carried by the web 21^a or the insulating medium. In this way the insulating medium is not materially compressed and a very light fluffy material may be employed, a material which in the same quantity is ordinarily useless beneath the sleeper by reason of the air being squeezed out of it. It is well understood by campers 110 that down and light wool quilts are very warm over the sleeper but are ordinarily

useless beneath him. In the present bed either may be employed with full satisfaction.

At the foot of the hammock, at least, and sometimes on parts of the edges, there is provided a strip 23 to which the blanket is pinned, or, if preferred, lacing may be employed. With this arrangement, it is impossible to kick the blanket out at the foot and one of the annoying features of camp beds is thus eliminated. This is a material improvement on all stretcher-type canvas beds since the heavy taut canvas makes the use of blanket pins very difficult, while the loose flap or strip greatly facilitates their use.

The present bed has many advantages. It is warm, dry and can be set up almost anywhere in a minute or two. It has been repeatedly used on ground where no other shelter could possibly have been erected. It is particularly adapted for river cruising because it can be used on steeply inclined banks, and even in dense thickets a space big enough to hang it can be found, or cleared in a short time. It rolls up in a compact bundle with all its bedding which is thus kept dry during the day. It can be made very light, far lighter than any other combination of tent and soft bed suitable for use on damp or rough ground without gathering browse or making other special preparations. By way of illustration, a bed of the type described and made with no particular attention to saving weight, weighs nine pounds, exclusive of bedding and insulation. By using aeroplane cloth for the hammock and the modern light tent fabrics for the tent, a weight approximating five pounds is attainable. The insulation under the hammock will be lighter than any of similar warmth used with any other form of bed, the blankets may be slightly lighter because the hammock wraps partly up the sides of the sleeper and thus narrow blankets will be satisfactory. The only beds and shelters which can give the same comfort weigh much more. For example, the ordinary army cot with tent attached weighs twenty pounds, without bedding, while any shelter tent and pneumatic bed will weigh at least ten pounds, and both these combinations involve more work in erecting and require more weight in bedding than does the present bed.

There are some further operative points of advantage brought about by the combination of the tent and hammock broadly considered. The hammock is, of course, flexible, and being under weight, is elastic in its action against strains. It thus affords

to the lower edge of the tent a very elastic support. Under heavy gusts of wind, therefore the tent has great capacity for yielding, not only by pulling up the hammock edges but by bodily swinging the whole hammock. The structure thus has all the properties which a tent should have to prevent damage by wind. The tent, also operates to steady the hammock so as to remove all of their well-known unsteadiness, especially when hung tight. It is quite possible, when the weather or flies compel, to dress and undress in the hammock without the least inconvenience, while were the tent removed and the hammock stretched as tight as it is normally used in the present device, this would require a good deal of balancing, and would be much more difficult.

I realize that considerable variation is possible in the details of the construction herein shown, and I do not intend to limit myself thereto, except as pointed out in the following claims, in which it is my intention to claim all the novelty inherent in the device as broadly as is permitted by the state of the art.

What I claim as new and desire to secure by Letters Patent is:

1. A camper's bed having, in combination, a hammock swingingly supported from its ends and comprising a central web, end attaching means and supporting cords radiating from said attaching means to the central web to form a reticulated triangular end, a tent independently supported above the hammock, secured to the sides of the hammock and extending only slightly therebelow, and a netting covering the reticulated triangular ends whereby ventilation is afforded from below when the tent is closed.

2. A camper's bed having, in combination, a tent-covered hammock, and an insulating body loosely held against the underside of the hammock and substantially uncomressed by the weight of the user.

3. A camper's bed having, in combination, a fabric web arranged and adapted to carry the weight of the user and an insulating body loosely held against and beneath said web so as to be substantially uncomressed by the weight of the user.

In testimony whereof I have hereunto set my hand and affixed my seal this 5th day of May, A. D. 1915.

RUSSELL WILES.
